UNITED STATES PATENT OFFICE.

JACOB S. LEWIS, OF BALTIMORE, MARYLAND.

STREET-CAR MOTOR.

SPECIFICATION forming part of Letters Patent No. 244,631, dated July 19, 1881.

Application filed November 9, 1880. (No model.)

To all whom it may concern:

Be it known that I, JACOB S. LEWIS, of the city of Baltimore and State of Maryland, have invented certain Improvements in Street-Car Motors, of which the following is a specification; and I do hereby declare that in the same is contained a full, clear, and exact description of my said invention, reference being had to the accompanying drawings, and to the letters of reference marked thereon.

This invention relates to the adaptation of the gas-engine to the propulsion of street-cars; and the said invention consists in combining in a street-car a gas-motor attached to the wheels of the car in such manner as to effect their revolution, a holder for the gas, and a receptacle for water to be used in cooling the engine-cylinder, as will hereinafter be more fully described.

In the further description of my said invention which follows reference is made to the accompanying drawings, forming a part hereof, and in which—

Figure I is a longitudinal section of a part of a street-car, showing the application thereto of my improvements. Fig. II is a plan of Fig. I, the car-body, however, being shown only in dotted lines. Fig. III is a view of a portion of the invention.

Similar letters of reference indicate similar parts in all the views.

A is the car-body, having the platform *a* extending from the front end thereof, as shown.

B is a gas-engine of any suitable design, the cylinder *b* of which is secured to the platform *a*. The piston-rod *c* of the engine is attached to the connecting-rod *d*, which, in turn, is coupled with the crank-pin *e*. The pin *e* is a part of the crank-shaft *C*, which is also the driving-axle of the car, it being connected to the driving-wheels *D D*, as hereinafter described. The engine is supplied with gas from a reservoir, *E*, formed in an extension, *F*, of the roof of the car, and with water for refrigerating purposes from a smaller receptacle situate in the roof proper, *G*, as shown in the drawings.

As the gas contained in the reservoir *E* is necessarily at a higher tension than that to be supplied to the engine the gas-supply pipe *f* is fitted with a pressure-reducing valve, *d*, and a smaller holder, *H*, (preferably an elastic bag, as shown,) for the expanded gas.

The expanded-gas holder may be located in any suitable position adjacent to the engine-cylinder; but for the sake of economy in space I place it in a box, *I*, which answers the purpose of a seat for the engineer.

In order to obviate the trouble arising from the frequent starting and stopping of the engine, I propose to keep the engine in constant motion, and connect the driving-wheels to the constantly-revolving axle by means of clutches, which may be connected and disconnected at the pleasure of the engineer. With this view I support the outer end of the axle in a sleeve, *h*, fastened to a bar, *i*, which at its upper end is provided with a cup-shaped flange, and place on the said flange an elastic ball, *k*, to serve as a spring. The bar *i* and its attachments are inclosed in a suitable frame, *l*, secured underneath the car-body, substantially as shown. The driving-wheels run loosely upon the sleeves *h*, and have an annular projection on their inner faces, into which clutches *K*, which may be slid longitudinally of the axle, but not turned independently thereof, are adapted to be forced. The contact of the clutches and the annular projections produces sufficient friction to communicate motion to the said wheels and drive the car.

Any proper mechanism may be used to effect the engagement and disengagement of the clutches and driving-wheels; but that which I prefer consists as follows: The hubs of the clutches are grooved, and rings *m* placed in the grooves, and toggle-bars *n* attached to the said rings by means of pins. The toggle-bars *n* are curved to clear the crank, and connected by rods *o* to a cross-head, *p*, at the front end of the car, to which an eccentric, *r*, is attached. The eccentric is turned by means of a vertical bar, *s*, having a cross-handle at its upper end in a convenient position for the engineer. The cross-handle is shown only in dotted lines, Fig. II. A sand-box, *L*, with a delivery-pipe, is used, as on locomotives, to increase the traction of the wheels when the same have a tendency to slip.

Parts of the invention not yet alluded to will be described and their uses set forth in the description of the operation of the invention which follows.

Before starting the car on its route the pressure-gas reservoir is filled through the nozzle

t, and the water-receptacle supplied by means of another nozzle, *u*. The engine is then put in motion, and it need not be stopped until the car has arrived at its destination, or until the gas-supply in the reservoir is practically exhausted. To start and stop the car it is only necessary to connect and disconnect the clutches with and from the car-wheels by means of the mechanism before described.

10 A governor on the engine regulates the speed of the engine as the load is increased or reduced.

In the foregoing I have described certain parts of the car which relate to the running-gear, and which are alike applicable to a steam and a gas motor. I do not, however, claim the 15 said mechanism herein, but will embody the same in a separate application, the object of

the extended description being merely to illustrate the adaptability of a gas-engine as a 20 motor for a street-car, and to show a proper connection between the motor and the car proper.

I claim as my invention—

In combination with a street-car, a gas-engine, a pressure-gas reservoir, and an expansive-gas receptacle connected by a pipe having a pressure-reducing valve therein, and a refrigerating water-tank having pipes leading to and from the said engine, all arranged substantially as and for the purpose herein specified.

JACOB S. LEWIS.
